DENTURE

Charles McNally, Pawtucket, R. I.

Application October 2, 1952, Serial No. 312,797

12 Claims. (Cl. 32—3)

1

This application is a continuation in part of my application Serial No. 221,094, filed April 14, 1951, now abandoned.

This invention relates to a denture either upper, lower, or partial, and more particularly to the holding of a denture in place in the mouth.

Many people experience difficulty in retaining dentures in place in the mouth, which results in considerable discomfort. Heretofore, there have been attempts to use suction to hold the denture in place. Various ways of applying this suction have been utilized but have resulted in only partial assistance. It is also found that the gums change in shape or contour by shrinking or other change so that an added difficulty is provided if suction is utilized along portions where this change rapidly occurs.

One of the objects of this invention is to provide a suction by means of extracting air at a single point from cavities on opposite sides of the denture and then closing this opening to retain reduced pressure therein.

Another object of the invention is to locate the suction cavities along the molar ridge area of the gums at a location which is the least likely to recede as the gums change in contour.

Another object of the invention is to provide a core for forming the cavity or recess in the denture, and which core may fit any gum by bending of the core to accommodate itself to different gum models.

Another object of the invention is to provide the recesses in the denture by using the core along with the same manner of procedure as heretofore has been utilized in providing dentures.

With these and other objects in view, the invention consists of certain novel features of construction, as will be more fully described and particularly pointed out in the appended claims.

In the accompanying drawings:

Figure 1 is a perspective view of a denture formed in accordance with this invention;

Figure 2 is a bottom plan view of the denture shown in Figure 1;

Figure 3 is a section on line 3—3 of Figure 2 prior to the cover or valve for the suction opening being positioned in place;

Figure 4 is a perspective view of a model with the cores positioned thereon and a conduit connecting each core;

Figure 5 is a sectional view showing the denture as being molded about the model with the core positioned thereon;

Figure 6 is a bottom plan view of the denture with the conduit and cores in place;

Figure 7 is a perspective view of a tube which is inserted in the cores and which connects the cavities of the denture;

Figure 8 is a perspective view of the cover which is used for sealing the opening in the tube;

2

Figure 9 is a perspective view of the shallow form of teeth which are used in the denture over the cavity portion thereof;

Figure 10 is a section on line 10—10 of Figure 4 showing the composite form of the core;

In proceeding with this invention, an impression is taken of the gums in the usual manner and sent to the dental technician. The dental technician then makes a model of the gums from the impression; then he positions on the model the cores with the conduit between, which cores serve to provide the cavities desired in the denture and then makes up a wax form of denture with the teeth in place; and sends it to the dentist for trial with the cores and conduit in the wax as shown in Figure 6. If the wax form is satisfactory, the final denture is formed from the usual material.

The cores which are utilized comprise deformable objects which may be made of lead or some easily bendable material which may be bent to the shape of the gums desired. Likewise, a conduit which connects these objects is of a bendable material so that it may be bent to follow the ridge of the gum. These cores are placed upon the model and are of such form that two cavities are formed in the denture with a connection between. The cores are then removed leaving the conduit in place so that when the denture is put in place, suction on the hole will serve to draw the air that is in the two cavities from the cavities to cause the denture to adhere firmly to the gums at the location of these cavities. There is no suction between the cavities. The recesses or cavities are formed along the molar area ridge, while the part between this molar area ridge where the major deformation of the gums occurs has no suction applied.

With reference to the drawings, 10 designates the model which is formed from the impression taken of the gums and substantially reproduces the gums upon which the denture is to fit, these reproduced gums being designated 11. The insert which is designated as a whole 12 comprises enlarged, cavity-forming cores 13, which are usually formed of deformable material such as lead 33 and rubber 34 so as to accurately fit the gum model 11. A conduit portion 14 also of deformable material and which is a tube connects the two cores 13, 13 and is of such shape that it may be bent to accurately fit the edge of the gums. A recess-forming part 15 for a cover may also be carried by the conduit 14. These cores so constituted are then placed upon the gum model 11 with a conduit connecting them, as shown in Figure 4.

The next step is to mold wax about the gum portion and core of the model made from the impression taken, as shown, with the teeth in position, which is a replica of the denture to be

formed, and this wax model with the insert 12 comprising the tube 14 and cores 13 in place as shown in Figure 6 is tried in the mouth and if found correct, then the denture is made from this mold by molding the usual denture-forming material about the gum portion and insert 12, as shown at 16 in Figure 5. Then the cores 13 are removed to leave the cavities 17, 17 formed in the legs 18, 18 of the denture with the conduit 14 connecting these cavities 17 (see Figure 2). The portion 15 provides an opening as at 20 in the denture. Opening 20 is located to expose a hole 22 in the tube. The opening 22 is controlled by means of a flap valve 24 which may be a piece of pliable, thin sheet rubber material attached in position by embedding one marginal edge thereof in the stock at one side of said opening and extending therefrom over said opening to close the same.

In use, the denture is placed in the mouth and by a sucking action about the opening 20, air will be withdrawn from the cavities 17, which sucking action will also have opened the valve 24, so that the pressure is very much reduced in the cavities, causing them to tightly hold against the gums. After the said withdrawal of air from the cavities, the valve 24 may then be moved toward the opening 22 to close the same as by being pushed by the tongue to engage against the stock at the sides of the opening 22. The atmospheric pressure acting against the valve 24 will tend to maintain the said valve in the closed position to hold the reduced pressure in the cavity to cause the denture to be held in place by atmospheric pressure acting thereon.

These cavities are preferably located so that they will come along the molar area ridge of the gum where there is the least likelihood of contraction due to changing of the gums.

The teeth 25 are usually embedded to extend a substantial distance into the gum portion of the denture 16, but at the location of the cavity 17, the teeth 26 are formed much shallower so as to allow for a larger cavity to be provided, that increased suction may be formed.

I claim:

1. An artificial denture having legs, means for holding the denture in place on the gums comprising the legs of the denture being provided with cavities in the gum-contacting side thereof along the molar ridge-engaging portion, an arcuate tube embedded in the denture connecting the cavities and provided with an opening along its length, said denture having a recess about said opening, a covering valve closing said opening to sustain a partial vacuum created in said cavities.

2. An artificial denture as in claim 1 wherein the teeth of the denture along the cavity portions of the denture are sufficiently shallow to avoid entering the said cavities.

3. An artificial denture as in claim 1 wherein there is one cavity only in each leg of the U of the denture.

4. An artificial denture as in claim 1 wherein there is one cavity only in each leg of the U of the denture and a single opening is provided in the tube.

5. The method of forming a denture which comprises positioning deformable cores and a connecting tube on a model, forming the gum portion of a denture about said model cores and tube so as to embrace and embed the tube therein, removing the cores while retaining the tube in place to leave cavities at the end of the tube.

6. The method of claim 5 which additionally comprises using a tube having a center opening intermediate its ends and positioning a covering valve over said opening.

5 7. An artificial U-shaped denture having legs provided with cavities in the gum-contacting side thereof along the ridge-engaging portion, an arcuate tube embedded in the denture connecting the cavities and provided with an opening along its length, a recess in the denture about said opening, and a valve means for controlling said opening, said valve means being operable to open position by a suction action thereon and maintained in the closed position by atmospheric pressure thereon to sustain a partial vacuum created in said cavities.

20 8. An artificial denture as in claim 7 wherein said valve comprises a piece of pliable, thin sheet material having one marginal edge thereof embedded in said denture at one side of said opening and extending therefrom over said opening to close the same.

25 9. An artificial denture as in claim 7 wherein said valve comprises a piece of pliable, thin sheet rubber material having one marginal edge thereof embedded in said denture at one side of said opening and extending therefrom over said opening to close the same.

30 10. The method of forming a denture which comprises positioning cores and a connecting tube on a model, molding a wax denture with artificial teeth set therein about the cores and tube for trial and thereafter maintaining the same teeth, cores, and tube in their relative position, withdrawing the wax therefrom, molding the final denture about the teeth, cores, and tube so as to embrace and embed the tube therein and thereafter removing the cores while leaving the tube in position to provide cavities in the denture.

40 11. The method of forming a denture which comprises positioning deformable tube and cores on a model, shaping the tube and cores to fit the model, molding a wax denture with artificial teeth set therein about the cores and tube for trial and thereafter maintaining the same teeth, cores, and tube in their relative position, withdrawing the wax therefrom, molding the final denture about the teeth, cores, and tube so as to embrace and embed the tube therein and thereafter removing the cores while leaving the tube in position to provide cavities in the denture.

50 12. The method of forming a denture which comprises positioning deformable cores on a model at spaced locations with one adjacent each end of the model, shaping the cores to fit the model, thereafter molding material about the cores and then removing the cores at the ends of the model to form spaced cavities at the ends of the denture.
